[57] CLAIM

The ornamental design for a lighting fixture, as shown and described.

DESCRIPTION

FIG. 1 is a side elevational view of a lighting fixture showing our new design, all sides being identical; FIG. 2 is a top plan view thereof; FIG. 3 is a bottom plan view thereof; and, FIG. 4 is a fragmentary side elevational view thereof, the side being cut away to show the interior structure thereof.

FIG. 1

FIG. 2

FIG. 3

FIG. 4
